United States Patent Office

Des. 192,979
Patented June 5, 1962

192,979

BOTTLE

George W. Worthington, Castro Valley, Calif., assignor to Owens-Illinois Glass Company, Toledo, Ohio, a corporation of Ohio

Filed Feb. 8, 1961, Ser. No. 63,866

Term of patent 14 years

(Cl. D58—6)

FIG. 1 is a side elevational view of a bottle showing my new design.

FIG. 2 is an end elevational view thereof.

FIG. 3 is a sectional view taken along the line 3—3 of FIG. 1.

FIG. 4 is a top plan view thereof.

The side and end not shown are the same as the respective side and end shown.

I claim:

The ornamental design for a bottle, substantially as shown and described.
